United States Patent Office.

CHARLES ROBINSON, OF BOSTON, MASSACHUSETTS.

Letters Patent No. 101,382, dated March 29, 1870.

PROJECTILE FOR TOY PISTOL.

The Schedule referred to in these Letters Patent and making part of the same.

To all whom it may concern:

Be it known that I, CHARLES ROBINSON, of Boston, Suffolk county, State of Massachusetts, have invented a new and useful Improved Toy Projectile; and I do hereby declare that the following is a full and clear description thereof, reference being had to the accompanying drawings and to the letters of reference marked thereon.

In the drawings—

Figure 1 is a side view of my projectile in use upon a toy gun constructed for the purpose.

The construction of this projectile is as follows:

A small solid ball, of wood or other hard and heavy material, is furnished with an elastic loop, A, attached to one side, and a non-elastic loop, B, which catches on the trigger, the elastic loop being caught upon a catch at or near the end, D, representing the muzzle of the toy-gun.

When the ball E is pulled back far enough to catch the loop B over the trigger, the elastic loop A is stretched sufficiently to give all the required momentum to the ball when released.

I am aware of the fact that other projectiles have been formed so as to slip over the rounded barrel of the toy gun, being operated by loops of elastic material; but I do not so form my ball, which has its line of guidance from only two points, viz: the trigger and the catch where the elastic loop is caught at D. In the case where the ball slides off from the barrel itself, the ball having a center hole, which fits over the barrel, I find these great objections: first, it is almost

impossible to keep a slim rod of sufficient length from warping, and, consequently, the toy does not project truly; again, the ball has to be made so large, to admit of its slipping over the barrel, that it is too large a mass to project with any success; again, the friction of the barrel prevents much of the projectile force from taking effect; and the ball with a hole through it is apt to chip and break.

In my improvements I form the ball solid, and thereby can make it small and heavy, instead of large and light. It is not apt to break, as there is no starting point for cracks, and it can be made of heavier material. It does not matter how much the barrel is warped, because, the point of sight being over the end catch, and the line of sight running directly from the center of the ball over this point, the projectile is always shot true to its aim. But the barrel may be made much heavier, as it is not necessary to limit its size as in the other case referred to, so that it will not even warp.

Now, having described my invention,

What I claim as new, and desire to secure by Letters Patent, is—

The combination of a solid ball, E, with elastic loop A and non-elastic loop B, as a toy projectile, to be used in the manner specified.

CHAS. ROBINSON.
